UNITED STATES PATENT OFFICE.

KENNETH J. TOBIN AND WILLIAM W. DARROW, OF CHICAGO, ILLINOIS, ASSIGNEES
TO CAMEL COMPANY, OF CHICAGO, ILLINOIS, A CORPORATION OF ILLINOIS.

LATCHING MECHANISM.

Application filed December 24, 1924. Serial No. 757,936.

To all whom it may concern:

Be it known that we, KENNETH J. TOBIN and WILLIAM W. DARROW, citizens of the United States, residing, respectively, at Chicago, in the county of Cook and State of Illinois, and at Chicago, in the county of Cook and State of Illinois, have jointly invented certain new and useful Improvements in Latching Mechanism, of which the following is a specification.

The present invention relates to latching mechanism.

More particularly the present invention relates to latching mechanism useful in connection with movable door jambs such as are used in railway freight cars of the box car type. Box cars for certain purposes, as, for example, box cars used in the transportation of automobiles and the like, must have side door openings of more than the usual width. Cars of this sort are commonly provided, in addition to the usual sliding door, with a secondary or supplementary door, which secondary or supplementary door is slidably movable to provide a door opening of extraordinary width but which may be stationarily held when a door opening of such extraordinary width is not required. In order to lock said supplementary door in its closed position it is common to provide a movable door jamb, which may be secured to said supplementary door or may move independently of said supplementary door. In either case said jamb should be capable of movement longitudinally of the car and should have means for locking same in position. Various means have been provided for the purpose of locking said movable jamb in the position which it occupies when the supplementary door is in closed position. Said position of the movable jamb will be referred to herein as the door closing position thereof.

An object of the present invention is to provide latching mechanism for a movable door jamb which will be positive in its action and which may be conveniently manipulated by an operator when he desires to move said door jamb to door opening position.

A further object is to provide latching mechanism for a movable door jamb which mechanism will invariably lock said jamb at its upper and lower extremities when said jamb is moved to door closing position.

A further object is to provide latching mechanism for a movable door jamb having latching means at both extremities of said jamb, which latching means may be positively controlled in a single movement either for latching or unlatching functions.

A further object is to provide latching mechanism for a movable door jamb which will simplify the work of the operator thereof.

A further object is to provide latching mechanism for a movable door jamb, together with operating means therefor, which latching mechanism will remain in unlatching position when once moved thereto in order that an operator may conveniently open said door, said structure having the advantage that if it should be decided not to open said door, the return of the latching mechanism to latching position may be conveniently and readily accomplished.

A further object is to provide latching mechanism for a movable door jamb, which mechanism may be removably held in place without the use of bolts or similar holding means.

Further objects will appear as the description proceeds.

Referring to the drawings—

Figure 1 is a fragmentary view of a car showing, in side elevation, a movable door jamb employing the principles of the present invention;

Figure 2 is a view of part of the structure shown in Figure 1, said view being taken in the direction of the arrows 2—2 of Figure 1;

Figure 3 is a fragmentary view illustrating, on an enlarged scale, the mechanism for latching a movable jamb at its lower extremity, together with the means for holding said latching mechanism out of latching position;

Figure 4 is a plan view illustrating a latch member used in carrying out the principles of the present invention; and

Figure 5 is a view of a modified detail of construction.

The numeral 10 indicates the side sill and the numeral 11 indicates the side plate of a railway box car. The numeral 12 indicates in its entirety a movable door jamb, which in the construction illustrated is a metal jamb. For purposes of clarity the supplementary door, above referred to, to

which the jamb 12 may be secured, has been omitted. It will be sufficient to state that the jamb 12 is adapted to be moved with a movement of translation longitudinally of the car. Figure 1 illustrates the movable jamb 12 in its home or door closing position. In this position certain latching mechanism cooperatively associated with the door jamb 12 engages with detent members stationarily mounted upon the side sill and side plate of the car.

The detent member associated with the side sill 10 is indicated by the numeral 13, and the detent member associated with the side plate 11 is indicated by the numeral 14. It will be noted that each of said detent members has the sloping portion 15, which sloping portions, as will be explained hereinafter, cooperate with the latching members carried by the jamb 12 to guide same into latching position. Each of said detent members 13 and 14 is provided with a positive stop portion 15' to limit movement to the right as viewed in Figure 1. Each of the detent members 13 and 14 is also provided with a recess 16 providing a wall 17. Said walls 17—17 of the detent members 13 and 14 are shown as being substantially vertical. Each of the detent members 13 and 14 is provided with the overhanging shoulders 18—18 on the two sides thereof, which cooperate with corresponding inwardly extending portions 19—19 at the extremities of the jamb 12, whereby when said jamb 12 is in its home or door closing position said jamb acts as a strut to prevent spreading between the side sill 10 and the side plate 11. Moreover, the interfitting parts at the extremities of the door jamb 12 and the detent members 13 and 14 provide guiding members for insuring the proper relationship between said detent members 13 and 14 and said door jamb 12 when said door jamb is being moved to closed position. The jamb 12 has housings 12'—12' at its extremities, which housings are identical in order to cut down the pattern equipment and the stock necessary to be carried on hand. The shoulders 18—18 are increasingly tapered from the sloping portion 15 rearwardly to the positive stop portion 15'. Preferably the upper faces of the shoulders 18—18 of detent 13 will be parallel with the lower faces of the shoulders 18—18 of detent 14. By reason of the tapered construction of shoulders 18—18, a slight braking action is had upon the jamb 12 as it is moved to home position, though it is preferable not to have such a large degree of taper that no binding is likely to occur.

Pivotedly mounted at the top of the jamb 12 is the latch 20. Said latch may have trunnions 21 projecting from the two sides thereof, whereby said latch may be rotat-

ably mounted. Said latch is also provided with the catch portion 22, which is shown as slightly undercut. Said latch is adapted to enter the recess 16 in the detent member 14 and to abut against the wall 17 of said recess. By reason of the fact that the catch portion 22 is undercut, the advantage is attained that a secure holding action may be had between the latch member 20 and the detent member 14, and that unlatching may be accomplished when desired without the necessity for exerting strong force. The other extremity 23 of the latch member 20 has a pair of substantially parallel walls arranged at an angle to the axis of the door jamb 12, for a purpose to be referred to hereinafter.

Pivotedly mounted on the jamb 12 at the lower extremity thereof is the latch member 24. Said latch member 24 is provided with the catch portion 25 extending from the lower side thereof. Said catch portion 25 has its face 26 beveled off slightly, whereby to simplify the matter of removing the catch portion from the recess 16 of the detent member 13. The latch member 24 is provided with the extremity 27. The numeral 28 indicates an operating member having the aperture 29 near its lower extremity, which aperture loosely receives the extremity 27 of the latch member 24. To hold the operating member 28 in position on the jamb 12 a plurality of vertically spaced bolts 28'—28' may be provided, which are secured to said jamb and extend through slots in said operating member 28. The ends of said slots will limit downward movement of said operating member 28 and its associated parts to prevent dragging along the floor of the car. At its upper extremity the operating member 28 is provided with a loop 30, which loosely encircles the extremity 23 of the upper latch member 20. Moreover, the operating member 28 is provided near its upper extremity with the wedge-shaped portion 30' adapted to have a wedging action with the extremity 23 of the upper latch member 20 to force same in a clockwise direction when said operating member 28 is moved upwardly. Said operating member is provided with a handle portion 31, by means of which said operating member 28 may be conveniently raised to perform its unlatching functions. By reason of the loop 30, when said operating member 28 is free to fall, it will positively engage the upper side of the extremity 23 of the upper latch member 20 to move same in a counterclockwise direction. Assuming that the door jamb 12 is in its home or door closing position, such counterclockwise direction of the latch member 20 will result in the engagement of the catch portion 22 thereof with the wall 17 of the recess 16 of the upper detent member 14.

Referring to Figures 3 and 4, it will be noted that the lower latch member 24 is provided with the trunnions 32-32 projecting from the two sides thereof. Said detent member is in the form of a yoke, the two arms thereof being indicated by the numerals 33-33. A pin 34 is mounted in the two arms 33-33 of the yoke, which pin forms the pivotal support of the cam member 35. Said cam member is loosely mounted upon the pin 34 and is weighted, whereby the force of gravity will cause said cam member 35 to tend to assume a predetermined position, which will be referred to herein as the supporting position of said cam member. When the door jamb 12 is moved from the left as the parts are viewed in Figures 1 and 3 toward the position indicated in said figures, the latch member 24 will be in its lowermost position and the cam member 35 will follow along, riding up upon the sloping surface 15 of detent member 13 and, when the jamb 12 is in home position, will assume an inclined position to the left of the pin 34, as indicated in dotted lines in Figure 3. When the latch member 24 is raised against the force of gravity, the cam member 35 will drop by gravity to the position shown in full lines in Figure 3. The cam member 35 will preferably be flattened on its lowermost surface as the parts are viewed in full lines in Figure 3, that is to say—the surface which is lowermost when said cam member is free to assume the position to which it is biased by gravity is flattened. It will be clear that when the latch member 24 is raised the cam member 35 will rotate from the dotted line position shown in Figure 3 to the full line position shown in said figure, in which full line position said cam member 35 is located above a flat portion of the detent member 13 and will act as a strut to hold the latch member 24 out of holding position, that is to say—said cam member 35 will hold the latch member 24 in a position such that the catch portion 25 will be free of said detent member 13. As the door jamb 12 is moved toward the left, that is—toward door opening position, there will be a tendency to raise the latch member 24 and its associated parts a small amount, and as movement is continued toward the left as the parts are viewed in Figure 3, the cam member 35 will be rocked to such an angular position that it will no longer act as a strut to support the latch 24, but will permit said latch 24 and its associated parts to drop by gravity. At this time, however, the catch portion 25 of the latch member 24 will be beyond the region where said catch portion will fall into the recess 16, for which reason it is unnecessary for the operator to maintain the operating member 28 in its upper position while he is moving the jamb 12 toward its door open-

ing position. Not only will the catch member 25 of the lower latch member 24 be in position to escape the recess 16 of the detent member 13, but the catch portion 22 of the upper latch member 20 will be in a position to escape the recess 16 of the upper detent member 14. In practice it has been found satisfactory to design the cam member 35 in such a way that movement of one-half inch of the jamb 12 toward the left will cause the release of said cam member 35 as a strut. The movement of one-half inch has been found to be sufficient to allow the catch portions 25 and 22 of the lower and upper latch members, respectively, to escape their corresponding recesses in the detent members 13 and 14. Of course, the proportions of the parts may be varied as preferred, in order to bring about the release of the latch members at the range of movement preferred.

The construction of the trunnions of the latch members 20 and 24 will now be described. It will be noted that said trunnions 32-32 are flattened, as indicated by the numerals 32'-32', but that in operation they have a bearing upon their rounded portions. The housings 12'-12' are provided with bearing lugs 36-36. Inasmuch as the housings 12'-12' are preferably made interchangeable, each of said housings will have a set of lugs 36-36 for use with latch member 20 and a different set for use with the latch member 24. Said latch members 20 and 24 are assembled in the housings 12'-12' before the jamb is secured in place. In assembling each of said latches will be rotated to a position such that its flattened portion will pass by the corresponding lug 36 in substantially parallel relationship with the adjacent face of said lug, the passageway 37 being provided for this purpose. In service, the latch members 20 and 24 will be in such positions that the trunnions 32-32 thereof cannot pass through said passageways 37-37, whereby the result is attained that the latches are securely retained without the use of bolts or similar retaining means. During the range of movement of the latch members while the jamb is in operative relationship with the car, the trunnions are securely retained. Only when the jamb is out of such operative relationship can the latches be turned to such positions that the flattened portions of the trunnions 32-32 are in position to pass through passageways 37-37.

It will be clear that by reason of the loop 30 at the upper extremity of the operating member 28 a positive jerk will be communicated to the upper latch 20 when the operating member 28 falls by gravity. By reason of said jerk said upper latch 20 is prevented from sticking and will invariably be moved in a counterclockwise direction when the

operating member 28 falls, whereby said latch member 20 will be operative to engage the sloping portion 15 of detent member 14 when the jamb 12 is moved to home or door closing position.

Not only is the upper latch invariably operative to engage with the recess 16 of the upper detent member 14, but the lower latch 24 is also invariably in position to engage 10 the sloping portion 15 of the lower detent 13, whereby to move into latching relationship when the door jamb is moved to home position. As referred to above, the cam member 35 will drag along the sloping portion 15 of the lower detent member 13 when the door jamb is being moved from the left toward the door closing position shown in Figures 1 and 3. When the door jamb has moved to closed position said cam member 20 20 35 will lie in the inclined position indicated in dotted lines in Figure 3, said cam member 35 having at this time no action as a strut. When it is desired to release the latching mechanism the operating member 28 will be 25 raised, which action will result in the clockwise rotation of the latch members 20 and 24 at the top and bottom, respectively, of the jamb. Said clockwise rotation will release the latches from their corresponding 30 detent members. Raising of the latch 24 will allow the cam member 35 to rotate to the position shown in full lines in Figure 3, whereby said cam member will act as a strut to hold the latch 24 in its unlatching position, shown in full lines in Figure 3. Not 35 only will the latch member 24 be held out of latching position, but the operating member 28 will be held in its uppermost position, whereby the wedge-shaped portion 30' of 40 said operating member 28 will hold the upper latch member 20 in its unlatching position. With both latches held out of latching position the operator may move the jamb to door opening position without bothering 45 further with the operating member 28 or the latches 20 and 24. If, as sometimes occurs, the jamb 12 is left spaced a short distance from its home position and a jar is received tending to move said jamb to home position, 50 the latches 20 and 24 will both locate themselves within the recesses of the corresponding detent members and lock the jamb. Expressed in other language, if the door jamb is moved sufficiently to allow the latch portion 25 of the lower latch member 20 to engage the sloping portion 15 of the detent member 13, or if said door jamb is moved a greater distance, the cam member 35 will be in a position to allow the latch portion 25 55 to drop into its recess 16. This feature is of decided advantage in railroad work, for the reason that it minimizes the effects of carelessness.

It should be noted also that the cam member 35 is housed within the lower latch mem-

ber 24 and within the lower portion of the movable jamb 12. By reason of this construction the cam member 35 is free from tampering and is protected from weather elements and from the lading of the car. 70

As noted hereinabove, the bolts 28' shown in Figure 1 will prevent the dragging of the operating member 28 and the latch member 24 along the floor of the car. Such dragging is prevented by reason of the fact that 75 the bolts 28' engage the upper extremities of the slots of the operating member 28 in which they ride.

Figure 5 discloses a cheaper and equally efficient structure for preventing the dragging of the operating member 28 and the latch member 24. According to the modification disclosed in Figure 5, the extremity 80 23 of the upper latch member 20 is provided with the shoulder portion 38, which carries 85 the loop 30 of the operating member 28. The shoulder portion 38 will limit downward movement of the operating member 28 and consequently will limit downward movement 90 of the latch member 24, whereby dragging of the operating members of the door jamb will be avoided.

Though preferred embodiments of the present invention have been described in detail, it will be clear that many modifications 95 will occur to those skilled in the art. It is intended to cover all such modifications that fall within the scope of the appended claims.

What is claimed is:

1. In a box car, in combination, a movable 100 door jamb, a pair of detent members for holding the two ends of said jamb, latch members at the two ends of said jamb for cooperation with said detent members, a member operable in a single movement for operating said latch members, one of said latch members being provided with automatically operating means for holding said operable member in its unlatching position after said operable member has been moved to said unlatching position. 105

2. In a box car, in combination, a movable door jamb, latching mechanism at the bottom of said jamb, said latching mechanism including a latch member mounted upon 115 said jamb and a relatively stationarily mounted detent member, said detent member having a sloping latch guiding portion and a latch receiving recess, said latch member being provided with an automatically operating holding member for holding said latch member out of latching position when said latch member is in position to otherwise locate itself within said recess. 120

3. In a box car, in combination, a movable 125 jamb, detent members for cooperating with the two ends of said jamb, latch members located at the two ends of said jamb for engaging said detent members, a member operable in a single movement for 130

simultaneously controlling said latch members, one of said detent members having a sloping latch guiding portion, and a recess for receiving the corresponding latch member, said last mentioned latch member being provided with automatically operating means for holding said latch member out of cooperative relationship with its corresponding detent member.

10 4. In a box car, in combination, a movable door jamb, a detent member for holding the bottom of said door jamb, a latch carried at the lower end of said jamb, said detent member having a latch engaging sloping portion and a latch receiving recess, said latch member being provided with a swinging holding member for holding said latch member out of cooperative relationship with said detent member.

15 5. In a box car, in combination, a movable door jamb, a detent member adapted to cooperate with one end of said jamb, a latch member carried by the corresponding end of said jamb, said detent member having a sloping latch engaging portion, and a recess for receiving said latch, said mechanism being provided with an automatically operating swinging member for holding said latch member out of cooperative relationship

20 30 with said detent member when said latch member has been moved out of such cooperative relationship.

6. In a box car, in combination, a movable door jamb, latch means located at the

35 two ends of said door jamb, a common member for positively actuating said latch members in a single movement, and a gravity actuated swinging member adapted to hold said common member in position to cause

40 said latch members to remain in unlatching position.

7. In a railway box car, in combination, a movable jamb, a detent member adapted to hold one end of said jamb, a latch member carried at the corresponding end of said jamb, said detent member having a sloping portion, and a latch receiving recess, said latch member being provided with a swinging holding member for holding said latch member out of cooperative relationship with said detent member, said holding member being shaped to permit a material movement of said jamb, such that when said latch member is released said latch member will escape engagement with said latch engaging recess.

8. Latch mechanism including a housing

and a latch member, said latch member having trunnions and said housing having holding means for said trunnions, said trunnions having flat portions, said holding means on said housing permitting the passage of said trunnions only when said flat portions are in a predetermined relationship with said holding means.

9. In a railway box car, in combination, a movable jamb, a latch member pivotally carried by said jamb, said latch member having trunnions, said jamb having bearing means for said trunnions, said latch member having a limited range of operative movement, said bearing means on said jamb and said trunnions being formed to permit the removal therefrom of said trunnions only when said latch member is moved beyond said range of operative movement.

10. In a railway box car, in combination, a movable door jamb, a latch member pivotally supported thereby, said latch member having trunnions provided with flat portions, bearing members carried by said jamb for holding said trunnions and providing a space sufficient for the passage of said trunnions only when said flat portions are in predetermined positions, said flat portions being so disposed upon said trunnions that said predetermined positions may be reached only when said jamb is removed from operative relationship with said car.

11. In a railway box car, in combination, a movable door jamb, latch members pivotally supported by said jamb at the upper and lower extremities thereof, and an operating member for said latch member capable, in a single movement, of positively moving said latch members to latching position or to unlatching position, said operating member being provided with stop means for limiting the downward movement thereof.

12. In a railway box car, in combination, a movable door jamb, latch means pivotally supported by said jamb at its upper and lower extremities, an operating member for controlling said latch members in a single movement, the upper of said latch members having a portion for holding said operating member from falling below a predetermined point.

Signed at Chicago, Illinois, this 13th day of December, 1924.

KENNETH J. TOBIN.

WILLIAM W. DARROW.
